Pls. 21

To all whom it may concern: Be it known that Abram Haney of the City of Troy in the State of New York have produced a new Ornamental Design for a coal Stove, and I do here by declare that the annexed and accompanying drawings are a full and accurate delineation of a Stove constructed after my design. The sides, not represented in the drawings, being similar to and symmetrical with the front excepting where differences are specified & shown in the said drawings.

I do not claim the Back plate and its ornaments but what I claim as my invention and desire to secure by Letters patent, is the combination and arrangement of ornamental figures and forms as represented in the annexed accompanying drawing, making an ornamental Design for a coal stove. Signed
